US0D1023325S

(12) **United States Design Patent** (10) Patent No.: **US D1,023,325 S**
(45) Date of Patent: ** Apr. 16, 2024

(54) **PAD**

(71) Applicant: **HYPERICIP SUBCO, LLC**, Irvine, CA (US)

(72) Inventors: **Alexander Joseph Aguiar**, San Diego, CA (US); **Trevor Austin Kerth**, San Diego, CA (US); **Ellen Posch**, San Francisco, CA (US)

(73) Assignee: **HYPERICIP SUBCO, LLC**, Irvine, CA (US)

(**) Term: **15 Years**

(21) Appl. No.: **29/813,603**

(22) Filed: **Oct. 29, 2021**

(51) LOC (14) Cl. **24-01**

(52) U.S. Cl.

USPC **D24/200**

(57) **CLAIM**

The ornamental design for a pad, as shown and described.

DESCRIPTION

FIG. 1 is a top perspective view of a pad;

FIG. 2 is a right side view thereof;

FIG. 3 is a left side view thereof;

FIG. 4 is a back elevation view thereof;

FIG. 5 is a front elevation view thereof;

FIG. 6 is a top, plan view thereof;

FIG. 7 is a bottom, plan view thereof; and,

FIG. 8 is a bottom perspective view thereof.

The short, broken lines shown in the figures illustrate portions of the pad that form no part of the claimed design. The dash-dot lines shown in the figures illustrate the bounds of the claim that form no part of the claimed design.

1 Claim, 5 Drawing Sheets
